ATTORNEY

UNITED STATES PATENT OFFICE.

BERNARD GOTHLBERG, OF WESTFIELD, NEW JERSEY.

DESIGN FOR A LIGHTING-FIXTURE.

51,781.

Specification for Design.

Patented Feb. 19, 1918.

Application filed December 3, 1917. Serial No. 205,260. Term of patent 3½ years.

To all whom it may concern:

Be it known that I, BERNARD GOTHLBERG, a citizen of the United States, residing in Westfield, in the county of Union and State of New Jersey, have invented a new, original, and ornamental Design for a Lighting-Fixture, of which the following is a specification, reference being had to the accompanying drawing, forming part thereof.

The drawing shows an elevation of the lighting fixture showing my new design.

I claim:

The ornamental design for a lighting fixture substantially as shown.

BERNARD GOTHLBERG.
